UNITED STATES PATENT OFFICE.

HERBERT V. SOUDERS, OF WILMINGTON, CALIFORNIA, ASSIGNOR OF ONE-HALF TO
JESSE M. FROST, OF LONG BEACH, CALIFORNIA.

JACK BOLSTER.

Application filed March 9, 1922. Serial No. 542,292.

To all whom it may concern:

Be it known that I, HERBERT V. SOUDERS, a citizen of the United States, residing at 5 Wilmington, in the county of Los Angeles and State of California, have invented new and useful Improvements in Jack Bolsters, of which the following is a specification.

My invention relates to vehicle jacks, and a purpose of my invention is the provision 10 of a bolster adapted to be associated with a jack of conventional form to occupy, when the jack is in active position, an interposing position between one of the springs of a vehicle and the head of a jack thus permitting of the direct application of the jack to a vehicle spring in effecting a lifting of a vehicle wheel and thereby eliminating the necessity of an operator crawling beneath a vehicle to apply the jack as is now the custom. 15

It is also a purpose of my invention to provide a jack bolster which is pivotally associated with the spindle of a jack so as to be extended when in active position, and 20 compactly folded with respect to the jack when in inactive position, the jack bolster thus constituting an integral part of a jack.

Although I will describe only two forms of jack bolsters embodying my invention and 25 point out the novel features thereof in claims, it is to be understood that various changes and modifications may be made herein without departing from the spirit and scope of such claims.

30 In the accompanying drawings,

Figure 1 is a view showing a portion of a motor vehicle having applied to the spring thereof a jack and one form of jack bolster embodying my invention.

40 Fig. 2 is an enlarged fragmentary view showing in side elevation the vehicle spring, bolster and jack spindle.

Fig. 3 is a top plan view of the bolster shown in the preceding views.

45 Figs. 4 and 5 are transverse sectional views taken on the lines 4-4 and 5-5, respectively, of Fig. 3.

50 Fig. 6 is a fragmentary view showing in side elevation the jack bolster hingedly associated with a jack spindle and also embodying my invention.

Similar reference characters refer to similar parts in each of the several views.

Referring specifically to the drawings, my invention, in its present embodiment, com-

prises a channel bar B formed of a single length of metal and including a linear portion b and a curved portion b'. The linear portion b is shown as tapered in width from its point of connection with the curved portion b', and its free end provided with a head 16 arranged transversely of the portion and including an upwardly extending flange 17 at the ends of which are formed upstanding projections 18. As clearly shown in Fig. 5, the web of the portion b is disposed lowermost with respect to the bar so that the edge flanges extend upwardly.

The portion b' is curved upwardly from its point of connection with the portion b, 70 and as clearly shown in Fig. 1, the web 19 thereof is disposed reversely with respect to the web of the portion b so as to provide a recess 20 upon the under side of the portion which is adapted to receive the head 21 of 75 any conventional form of jack. As the greatest pressure is exerted upon this curved portion b', it is preferably reinforced by means of intersecting ribs 22 as clearly shown in Fig. 3, these ribs being formed integral with the web 19 as will be understood. The free end of the portion b' is provided with an upstanding flange 23, and the opposite ends of this flange are formed with 80 upstanding projections 24.

In the applied position of the bolster as shown in Figs. 1 and 2, the projections 18 and 24 serve to maintain the bolster against lateral displacement with respect to the spring designated at S of the vehicle, and 90 as particularly shown in Fig. 2, the bolster contacts with the spring only at flanges 17 and 23.

In practice, any conventional form of jack such as the jack J shown in Fig. 1 is associated with the bolster so that its head 21 is disposed within the recess 22, and with the bolster applied to the spring as shown, it will be clear that by actuating the jack the spindle 25 thereof when moved upwardly will 95 cooperate with the bolster and spring in effecting an elevation of the vehicle wheel.

It is to be particularly noted that the deposition of the recess 22 is such that the jack J can be applied to the bolster at a 100 point in the rear of the vehicle wheel, thereby permitting of the actuation of the jack from a point in the rear or at the side of the vehicle, thus eliminating the necessity of the operator crawling beneath the vehicle to 105 110

apply the jack as is the present practice. The length of the bolster B is such as to properly distribute the pressure exerted by the jack along the length of the spring thereby preventing distortion of the spring and a separation of its leaves during the lifting operation.

In the form of bolster just described, it is adapted to be applied to and removed from the spring independently of the jack, as it is my intention that this bolster be adapted for use with any jack of conventional form. However, in order that the bolster may constitute an actual part of any conventional form of jack so as to prevent loss thereof and to facilitate the application and removal thereof to the spring, the bolster is hingedly connected to the spindle of a jack in the manner shown in Fig. 6. As here shown, the upper end of the spindle 25 is provided with an ear 26 instead of the head 21, and this ear is adapted to be inserted between a pair of spaced ears 27 formed on the bar B through which a pivot pin 28 is extended.

By this construction it will be clear that the bolster can occupy an extended position in which it is disposed substantially at right angles to the spindle for application to the spring, or a folded position in which it is disposed substantially parallel to the body of the jack so that it may be easily stored within the compartments provided for this purpose in a vehicle.

What I claim is:

1. In combination, a vehicle including a spring, a jack adapted for arrangement beneath the spring and in the rear or advance of the adjacent wheel, and a bolster interposed between the head of said jack and spring and formed with a jack head receiving portion adjacent to the outer end thereof whereby the operating lever of the jack is so disposed as to permit actuating thereof without reaching beneath the vehicle.

2. A bolster of the character described

comprising a channel bar including a linear portion and a curved portion, the webs of said portions being reversely disposed to provide a recess at the inner side of the bar 50 and at a point intermediate of its ends.

3. A bolster of the character described comprising a channel bar including a linear portion and a curved portion, the webs of said portions being reversely disposed to 55 provide a recess at the under side of the bar which is accessible from one end of the bar, transverse and upstanding flanges formed on the ends of the bar, and upstanding projections formed on the ends of the flanges. 60

4. In combination, a jack including a spindle and a bolster adapted for use in connection with a jack and movably secured to the spindle to occupy an extended position in which it is disposed substantially at right 65 angles to the spindle, and a folded position in which it is disposed substantially in parallelism to the spindle.

5. A bolster adapted for use in connection with a jack and comprising a bar U-shaped 70 in cross section for a portion of its length and of inverted U-shape in cross sections for the remainder of its length.

6. A bolster comprising a channel bar having upturned ends and the web thereof 75 reversely disposed from a point between its ends to provide on the under side of the bar a recess portion adapted to receive the head of a jack.

7. A bolster comprising a bar U-shaped in 80 cross section for a portion of its length and of inverted U-shape in cross sections for the remainder of its length, the first portion being of linear form and the remaining portion curved. 85

8. A bolster comprising a bar having a recess in its under side which is accessible from one end of the bar to permit the application of a jack thereto.

In testimony whereof I have signed my 90 name to this specification.

HERBERT V. SOUDERS.
